CABINET FOR RADIO RECEIVING APPARATUS

Filed Aug. 23, 1928

*Inventor
Arthur Atwater Kent
By Cornelius L. Ellet
Attorney.*

UNITED STATES PATENT OFFICE.

ARTHUR ATWATER KENT, OF ARDMORE, PENNSYLVANIA.

DESIGN FOR A CABINET FOR RADIO RECEIVING APPARATUS.

Application filed August 23, 1928. Serial No. 27,942. Term of patent 14 years.

To all whom it may concern:

Be it known that I, ARTHUR ATWATER KENT, a citizen of the United States, residing at Ardmore, county of Montgomery, State of Pennsylvania, have invented a new, original, and ornamental Design for a Cabinet for Radio Receiving Apparatus, of which the following is a specification, reference being had

to the accompanying drawing, forming part hereof.

The figure is a perspective view of a cabinet showing my design.

I claim:

The ornamental design for a cabinet for radio receiving apparatus, as shown.

ARTHUR ATWATER KENT.
